United States Patent Office

Des. 175,887
Patented Oct. 25, 1955

175,887

VENDING MACHINE

Clare E. Hodgman, Mamaroneck, N. Y., assignor to Coca-Cola Company, New York, N. Y., a corporation of Delaware

Application February 21, 1955, Serial No. 34,595

Term of patent 14 years

(Cl. D52—3)

—FIG. 1—

—FIG. 2—

Fig. 1 is a front view of a vending machine, embodying my new design; and

Fig. 2 is a side view thereof.

The opposite side of the vending machine is substantially the same in appearance as the side shown, and the rear is unadorned.

I claim:

The ornamental design for a vending machine, as shown and described.

UNITED STATES PATENT OFFICE
CERTIFICATE OF CORRECTION

Design
Patent No. 175,887

October 25, 1955

Clare E. Hodgman

It is hereby certified that error appears in the above numbered patent requiring correction and that the said Letters Patent should read as corrected below.

The name of the assignee was erroneously described and specified as Coca-Cola Company, New York, N. Y., a corporation of Delaware" as assignee, whereas said name should have been described and specified as -- The Coca-Cola Company, New York, N. Y., a corporation of Delaware.

Signed and sealed this 3rd day of January 1956.
